UNITED STATES PATENT OFFICE.

MOSE FISHER, OF PLAIN, NEW MEXICO.

COMBINED FOLDING TABLE AND LUGGAGE CARRIER.

Application filed April 25, 1924. Serial No. 708,969.

To all whom it may concern:

Be it known that MOSE FISHER, a citizen of the United States of America, residing at Plain, in the county of Quay and State of New Mexico, has invented new and useful Improvements in Combined Folding Tables and Luggage Carriers, of which the following is a specification.

It is a purpose of the present invention to provide, in a combined folding table and luggage carrier for automobile running boards, a construction consisting of a frame to be fastened to the edge of the running board and in reinforced connection with the fenders, in conjunction with folding leaves carried by the frame, said leaves, when collapsed, constituting the side of the carrier to prevent falling out of the luggage, and when said leaves are extended, they act as a table, so that when the automobile is parked, tourists may serve their meals on the table.

Another purpose is to provide collapsible braces for the leaves, the braces, when collapsed and the leaves folded down, assuming positions behind the leaves.

Still another purpose is the provision of means for holding the leaves collapsed or folded.

A further purpose is the provision of means, such as hooks and thumb-screws or screw-eyes, for assisting in holding the leaves of the table opened and in horizontal positions ready for use.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in perspective of a portion of an automobile, showing the running-board and illustrating the combined folding table and luggage carrier applied, the table being opened.

Figure 2 is a view in elevation, showing the table collapsed.

Figure 3 is a sectional view on line 3—3 of Figure 1, also illustrating the leaves of the table opened and showing how the leaves are braced and supported upon the frame of the carrier.

Figure 4 is a sectional view on line 4—4 of Figure 2, more clearly showing the collapsed positions of the leaves and the collapsed positions of the braces. 60

Referring to the drawings, 1 designates the side of an automobile, 2 denotes the running-board and 3 portions of the fenders.

The combined folding table and luggage carrier comprises a frame 4, the upper and lower rails 5 and 6 of which are secured at 7 to the outer edges of the running-board and the fenders, there being vertical bars 8 connecting the upper and lower rails or bars 5 and 6 to insure a rigid structure. Suitable hinges 9 are carried by and secured to the upper rail 5 of the luggage carrier frame and are, in turn, connected to the leaf 10 of a table 11.

The table consists of leaves 10 and 10^a which are hingedly united at 9^a so that the leaf 10^a may fold outwardly upon the leaf 10 when the leaf 10 is folded downwardly adjacent the side of the frame 4, as in Figure 4. Obviously, when these leaves are 80 opened and supported in horizontal positions, they constitute a table on which meals may be served, that is, when the automobile is parked. When the leaves are folded, as in Figure 2, they constitute the side of the 85 luggage carrier, acting to prevent luggage falling out between the upper and lower bars or rails.

Also carried by the upper bar or rail 5 of the luggage carrier are hooks 12 which 90 engage with thumb-screws or the like 13 which are carried by the under face of the leaf 10, assisting materially in holding the leaves in open spread positions. However, to further assist in holding the leaves in 95 open spread positions and at the same time reinforce them, braces 14 are provided. The braces 14 consist of the hinged sections 15 and 16, the latter being hingedly connected to the lower rail of the luggage 100 carrier frame, as at 17, while the former engage with notches 18 formed in the under surface of the leaf 10 of the table when the leaves 10 and 10^a are in open spread positions. The braces, when the leaves are 105 folded as in Figure 2, collapse and assume positions behind the two leaves. Since the sections 16 of the braces are hinged to the upper edge of the lower bar 6, the end edges of the braces abut the upper edge of the lower bar 6, thereby supporting the braces in 110 perpendicular positions when the sections

of the braces are folded and the leaves folded as in Figure 4. In this way, the sections 15 and 16 of the braces are prevented from falling inwardly upon the running-
5 board.

Carried by the outer face of the lower bar 6 of the frame is a thumb-screw 20 and hingedly mounted adjacent the lower portion of the lower bar or rail 6 of the luggage carrier frame is a clasp or strap 19. This clasp or strap has an elongated opening through which the thumb-screw 20 passes when the leaves are folded, and by imparting a partial or half turn to the
10 thumb-screw, the edge of the head of the thumb-screw overlies the clasp and holds it in a latched position, thereby retaining the leaves in collapsed positions due to the fact that the end portion of the clasp overlies
15 the leaves when folded.

When the leaves are unfastened by turning the thumb-screw 20 so that the head thereof will register with the slot in the clasp, the leaves may be disposed in horizontal extended positions and the braces placed to reinforce the leaves. The hooks 12, when the leaves are extended in horizontal spread positions, engage with the thumb-screws 13, thereby further assisting in holding the
20 leaves in position.

The invention having been set forth, what is claimed is:

1. In a combined folding table and luggage carrier for automobiles, the combination with a frame secured to the outer edges of the running-board and the fenders, of folding table leaves, one being hingedly mounted on the upper edge of the frame, said table leaves being hingedly united
35 whereby their adjacent edges may abut and thereby reinforce and support the table leaves in horizontal positions.

2. In a combined folding table and luggage carrier for automobiles, the combination with a frame secured to the outer edges of the running-board and the fenders, of

folding table leaves, one being hingedly mounted on the upper edge of the frame, said table leaves being hingedly united whereby their adjacent edges may abut and thereby reinforce and support the table leaves in horizontal positions, and means for reinforcing and supporting the table leaves when extended horizontally.
50

3. In a combined folding table and luggage carrier for automobiles, the combination with a frame secured to the outer edges of the running-board and fenders, of folding table leaves mounted upon the upper rail of said frame, one leaf being foldable
55 upon the other which, in turn, folds outwardly and downwardly adjacent the outer face of the frame, means for reinforcing and supporting the table leaves in horizontal extended positions, a fastener carried by
60 the lower part of the frame, and means also carried by the lower part of the frame co-operating with the fastener for holding the leaves in collapsed positions.
65

4. In a combined folding table and luggage carrier for automobiles, the combination with a frame secured to the outer edges of the running-board and fenders, of a pair of table leaves, one being hingedly mounted on the upper edge of said frame, said leaves being hingedly united, the construction and arrangement of the hinges uniting the leaves being such that the adjacent edges of the leaves abut, thereby reinforcing each
70 other when in horizontal positions, collapsible braces for supporting the leaves in horizontal open spread positions, means additionally connecting one of the leaves to the frame and additionally reinforcing them, said leaves being foldable adjacent the outer face of the frame while the braces may be collapsed behind the leaves, and means for holding the leaves in said collapsed positions.
75

In testimony whereof he affixes his signature.
90

MOSE FISHER.
